DESIGN FOR A GAME BOARD

William H. Kipp, Cincinnati, Ohio

Application October 19, 1937, Serial No. 72,320

Term of patent 3½ years

To all whom it may concern:

Be it known that I, William H. Kipp, a citizen of the United States, residing at Cincinnati, in the county of Hamilton and State of Ohio, have invented a new, original, and ornamental Design for a Game Board, of which the following is a specification, reference being had to the accompanying drawing, forming a part thereof.

The figure is a plan view of the game board showing my new design. The article is of no appreciable thickness.

I claim:

The ornamental design for a game board, as shown and described.

WILLIAM H. KIPP.
